UNITED STATES PATENT OFFICE

GEORG BÜHLER, OF VIENNA, AUSTRIA

COMPOUND MOLD FOR CASTING METAL BODIES

Application filed October 29, 1928, Serial No. 315,818, and in Germany November 4, 1927.

This invention has reference generally to molds and more particularly it relates to a compound mold for casting hollow metal bodies.

5 The invention has for its object to provide a device of the above character embodying a plurality of chilled molds having smooth outer faces arranged on each so that the same may be arranged in intimate contact with 10 each other and connected together to form a single unit which facilitates an easy filling from above with molten material through a common funnel.

More specific objects of the invention consist in the provision of improved means for reinforcing and securing the upper portions of the several molds when arranged to form a unit as well as means for anchoring the molds to a base.

20 Other objects as well as the nature, characteristic features and scope of the invention will be more readily apparent from the following description taken in connection with the accompanying drawings and pointed out 25 in the claims, forming a part of the specification.

A form of construction of a chill mold according to the invention is illustrated, by way of example, in the accompanying drawings in 30 which:

Fig. 1 shows one single chill mold with core in sectional elevation,

Fig. 2 shows a plan view of a unit comprising eight chill molds.

35 Fig. 3 shows the lower end and

Fig. 4 the upper end of a chill mold.

The chill molds are usually constructed of cast iron castings. 1 is the chill-mold casing with ribs 2. The lower supporting member 3 is rounded at 4 and recessed at 5 for the accommodation of the bottom 6, of the core rod 7. Around the core rod is the body of the core 8. 9 is the centering ring of the mold. The core is held securely by means of the centering ring 9 and the lower member 6. The metal, which fills up the intermediate space 11 between the core and the walls of the mold is poured in at 10. 12 is the overflow for the molten metal.

40 A combined unit of eight chill molds is

shown in Fig. 2. These chill molds are secured to one another by screw bolts 17 which pass through the flanges 13 in each chill mold. The chill molds are smoothed on the whole length of their sides 14 where they abut 55 against one another so that they are adequately connected together to form a single unit and that the rates of cooling are equal on all sides of the chill molds. The unit formed by the eight chill molds is held together by 60 a strong band 18 which lies in the recess 15 between the ribs 2. Below this band there is another weaker band 19 around the chill molds. The molds stand on a common base 20 to which they are fixed by means of screw 65 bolts 21, which pass through the lugs 16 of the chill molds. Only two screw bolts 21 are used, so that the molds have a little play. All the chill molds are filled through a common funnel. The overflows are so arranged 70 for the individual chill molds that each mold is filled up completely in 15 to 20 seconds. Immediately after the material begins to contract in length and diameter. Strains are prevented since the core is resilient and yields in 75 all directions. As a matter of fact the loosely stamped middle portion of the core is generally broken away from the upper hard portion of sand.

The perfectly uniform cooling on all sides 80 is secured by the disposition of the ribs, the smoothing of the contact surfaces of the individual chill molds and the correct choice of the wall thicknesses of the molds. The wall thickness, moreover, must be so 85 chosen that the casting can solidify in the correct time. In this connection it is to be observed that the thickness of the mold varies according to the wall thickness of the flanged 90 sockets to be made. The thickness of the wall of the chill mold is 25 millimeters for a flanged socket having a wall thickness of 12-15 millimeters. If flanged sockets with a wall thickness of 16-20 millimeters are to be cast, chill molds having a wall thickness 95 of 30 millimeters come into consideration. A somewhat sudden cooling takes place when the walls are constructed of cast iron and have the thicknesses indicated in the diagram. However, this is essential in order to obtain 100

a material which will draw well, especially pure bronze draw-holes which can be further drawn to a sufficient extent. In all cases, however, stresses must be prevented; these 5 lead to the formation of cracks and render impossible the further drawing of the draw-holes obtained. It has been ascertained that draw-holes cast in the above described chill-molds with the aid of resilient cores have 10 smooth and unbroken skins both inside and outside. Experience shows, however, that this is the necessary requirement for further working by drawing. Draw-holes produced according to the present invention may be 15 drawn out until the walls are $\frac{1}{4}$ or $\frac{1}{5}$ of the original thickness and sometimes even a smaller fraction thereof. Hitherto this has been quite impossible with tubes of pure bronze. This capability of being further 20 worked is not a property in draw-holes cast in sand molds.

What I claim is:

1. A compound mold for casting metallic bodies comprising a plurality of cylindrical 25 chill molds having substantially opposed surfaces made smooth and contacting with each other, spaced lugs extending rearwardly from each of the molds and screw bolts passing through the lugs on adjacent molds so 30 as to combine all of the molds into one unit to facilitate an easy filling from above with molten material through a common funnel.
2. A compound mold as claimed in claim 1, wherein each mold is provided with spaced 35 horizontal ribs forming a substantial groove, the ribs on the mold aligning with each other in combination with a band extending about all of the molds and lying within the groove formed by the ribs, and means for 40 connecting the ends of the band together.
3. A compound mold as claimed in claim 1, wherein a base is provided which is common to all of the chill molds, flanges extending rearwardly from the molds adjacent 45 the corners of the base, and means for anchoring said flanges to the base, substantially as and for the purposes set forth.

In testimony whereof I have signed my name to this specification.
